United States Patent Office.

SAMUEL B. FAY, OF NEW YORK, N. Y.

Letters Patent No. 96,410, dated November 2, 1869.

IMPROVEMENT IN TAGS.

The Schedule referred to in these Letters Patent and making part of the same.

To all whom it may concern:

Be it known that I, SAMUEL B. FAY, of New York, in the county of New York, and in the State of New York, have invented certain new and useful Improvement in Tags; and do hereby declare that the following is a full, clear, and exact description thereof, reference being had to the accompanying drawings, and to the letters of reference marked thereon, making a part of this specification.

The nature of my invention consists in the construction of perforated plates of metal or other suitable material, to be substituted for the ordinary metal eyelet in the manufacture of tags, &c.

In order to enable others skilled in the art to which my invention appertains, to make and use the same, I will now proceed to describe its construction and operation, referring to the annexed drawings, in which—

Figure 1 is a view of a tag with my improved plate attached, and

Figure 2, is a view of the plate.

A represents an ordinary tag, made in any of the known and usual ways, but without the usual eyelet.

B is a plate, made of metal or other suitable hard material, of something like the shape shown in fig. 2, having one hole at one end, and two holes at the other.

In the tag A are made holes to correspond with the holes in the plate B.

The cord C is inserted in the manner shown in fig. 1, that is, the two ends of the cord are passed one through each of the holes in one end of the plate and through the corresponding holes in the tag; both ends are then brought back through the tag and through the single hole in the other end of the plate.

By this improvement, the cost of making is greatly decreased, and the labor of inserting entirely obviated, as, in its use, in the manufacture of tags and direction-labels it is applied, at the same time it is very strong.

The small metal tie used on the string is also dispensed with, the same result being obtained by passing the cords through the upper hole of the plate.

Having thus fully described my invention,

What I claim as new, and desire to secure by Letters Patent, is—

The perforated plate B, made of metal or other suitable material, as a substitute for the ordinary metal eyelet in the manufacture of tags, &c., substantially as herein set forth.

In testimony that I claim the foregoing, I have hereunto set my hand and seal, this 30th day of August, 1869.

SAMUEL B. FAY. [L. S.]
